SIGNALING

Harold O. Peterson, Riverhead, N. Y., assignor to
 Radio Corporation of America, a corporation
 of Delaware

Application June 8, 1946, Serial No. 675,348

18 Claims. (Cl. 178—66)

1

The invention disclosed herein concerns signalling by means of electrical currents and is particularly concerned with receiving signals of the type known in the radio art as frequency shift telegraphy, frequency shift facsimile and similar signals.

In frequency shift systems signals are sent by alternately keying on and off currents of different frequencies one of which represents mark and the other of which represents spaces between mark signals. The keyed currents may be derived from a common source the frequency of which is shifted between two values by the keying energy. The currents may also be obtained by the use of two alternating current sources of different frequency, from which output is taken alternatively in accordance with keying energy.

The keyed currents may be of high frequency or low frequency. In the latter case they may appear as tone modulation on energy of carrier wave frequency for radiation or line transmission.

At the receiver the frequency shifted currents are amplified and demodulated to recover currents of the mark and space frequencies or currents representing mark frequency and space frequency. The signals are a form of frequency modulation and at the receiver are subjected to a frequency selection or discriminating action to recreate pulse energy or direct current potentials of varying magnitude which corresponds to the signals used at the transmitter for keying.

The general broad object of my invention is improved frequency shift telegraphy reception.

In signalling systems of this type if the mean frequency of the frequency shifted currents drifts the characteristic of the detector is no longer symmetrically related to the average or center frequency and the direct current potentials vary non-symmetrically with respect to a base value so that telegraph bias is introduced because the tube circuits coupling the same to recording apparatus are no longer excited as intended being direct current biased or weighted in one or the other direction depending on the direction of drift of the center frequency. This reduces the effectiveness of the recording apparatus. In my U. S. application Serial #630,428, filed Nov. 23, 1945 I have shown an improved means for preventing such slow variation in the mean frequency of the currents from upsetting the proper action of the coupling tubes and recording apparatus actuated by the signals. This means involves the use of a relatively large condenser in a network having a long time constant between the demodulator output and coupling

2

tubes controlling the recording apparatus. This condenser then responds to changes in magnitude of the applied direct current component as well as to changes in polarity thereof. At the network output then an alternating current component is supplied which varies nearly symmetrically about a base value even when the detector output is biased off, i. e. has a direct current bias caused by the carrier drift.

- 10 An object of the present invention is an improved means for preventing this slow drift in the carrier frequency from introducing telegraph bias in the signal and hindering proper operation of the coupling tubes and recording apparatus.
- 15 To attain this object I provide in the coupling between the detector output and the recording apparatus a network of the nature described above for reducing somewhat the effects of slow changes in the mean frequency of the signals.
- 20 This means is similar in makeup and function to that disclosed in my aforementioned application and is used in combination with additional means which I provide in accordance with the present invention for limiting excursions of the alternating current component, at the network output, representing mark and space frequencies beyond selected values in either direction. In other words in the present improved system I eliminate the direct current component from
- 25 the energy representing the demodulated signals and also clamp the resulting potential within fixed limits of variation in both directions of the signal excursions. When this is done exact centering of the signal in the receiver is no longer
- 30 necessary to provide potentials of reversing polarity for controlling the coupling tubes between the detector output and the recording apparatus. Moreover if the signal wave before detection is sufficiently off center the said potentials of reversible polarity may not vary symmetrically or as desired about a base value. An object of the present invention is to provide means to recenter these potentials.

Where the potentials are used to control a tone keyer tube, potentials which vary non-symmetrically with respect to a base value are desirable because the tube may be designed to operate best with a cut-off voltage the absolute value of which is less than the positive voltage at which the tube is saturated as desired for square wave keying. A further object of the present invention is to provide means for adjusting the excursions of the signal relative to a base value as desired.

These objects are attained in accordance with the present invention by use of bias fixing means in the coupling circuits of a direct current amplifier. The bias fixing means comprises a pair

of uni-directional devices connected in opposed polarity across the coupling circuits and arranged in condenser charging and discharging paths including resistances across which the potentials varying as desired with respect to a base value are developed.

When my improved bias fixing means is in the grid circuit of a coupling tube the said tube may draw grid current when its grid voltage swings positive and no grid current when its grid swings negative. The coupling tube discharge path then introduces a non-symmetrical effect in the coupling circuits. The grid resistance may limit the grid current to a small value but an object of my invention is to correct entirely this non-symmetrical operation. To do this I provide an additional electron discharge device so arranged in the network as to draw a compensating current when the coupling tube is biased to cut-off. The arrangement is such that equal leakage paths are provided for positive and negative swings of the grid potential of the coupling tube. Then the discharge paths have no effect on the bias centering.

The network feeding the control potentials to the grid of the tone keyer tube includes a capacitor. When signals are coming in a negative bias is developed and set up on the control grid of the control tube. At the end of signalling this capacitor in the grid circuit of the control tube may discharge, permitting a somewhat less negative voltage to build up on the grid of the control tube. Then disturbances and noises in the system might actuate the recording apparatus. A further object of my invention is to provide means to shut off the recording apparatus control tube at all times when the signal has been off a predetermined time interval. This means is in a sense a squelching circuit actuated in the absence of signals to disable or stop operation of the control tube.

In describing my invention in detail reference will be made to the attached drawings wherein Fig. 1 illustrates a frequency shift detector and tone keyer, with a coupling network between the detector output and the tone keyer tube arranged in accordance with my invention. This network includes a condenser of substantial size arranged to eliminate the effects of an off center wave on the detector input. This embodiment also includes bias adjusting or clamping tubes operating on peaks of the signal excursions in both directions.

Figure 2 is a modification of the arrangement of Figure 1. In Fig. 2 I illustrate the means for compensating the effect of current flow in the grid circuit of the coupling tube when the same swings positive.

Figure 3 is a modification of the arrangement of Figs. 1 and 2 and includes an additional tube for returning or holding the tone keyer tube in the space condition in the absence of signals.

Figure 4 illustrates by signal voltage curves plotted against time and tone keyer bias voltage curves and tone keyer alternating current output curves the manner in which my improved circuit arrangements operate to eliminate need of centering of the signal voltage on the detector input and elimination of the effects of miscentering thereof and also the manner in which the signal is squared off by my improved circuits before application of the same to the tone keyer.

Figures 5 and 6 are modifications of the arrangement of Fig. 1 and illustrate application of my invention to frequency shift signalling sys-

tems as disclosed in Schock U. S. application Serial #632,978 filed December 5, 1945. In these embodiments my signal centering clamping and so forth network is connected to the output electrodes of the gating stages. The gating stages are excited at their inputs by detected frequency shifted signals.

In Figure 1 rectangle 10 represents a current amplitude amplifier and limiter operating at an appropriate frequency, to amplify and limit frequency shifted currents the frequency shifts of which are in accordance with telegraphy, facsimile or similar signals. The limiter 10 might for example operate at 50 k. c. or higher or lower or even as low as a tone frequency shifted in accordance with the signal. The limiter 10 supplies output which is impressed on equipment in 12 including a frequency discriminator. In this discriminator frequency shifts of the tone or higher frequency current are converted into corresponding frequency and amplitude shifts. This frequency discriminator may be of the off-tune type as in Conrad's U. S. Patent #2,057,640 or modifications thereof or as disclosed in the Seeley U. S. Patent #2,121,103 or modifications thereof. The detector in 14 coupled with the discriminator output may be of any approved type such for example as shown in said patents. The detected signals at the output may vary above and below substantially zero potential and these variations may be symmetrical when the received signal as applied from unit 10 to the apparatus in unit 12 is centered on the characteristic of the frequency discriminator in 12. These potential variations appear across the resistor R1 and are supplied by coupling condenser C and series resistor 15 to the control grid 17 of an electron discharge device 18.

The tube 18 may be a coupling tube supplying output to recording apparatus such as a teletypewriter or to an outgoing line. In the embodiment discussed tube 18 is a tone keyer and its anode circuit includes a resistance 20 in the grid biasing circuit of the tone amplifier tubes 22 and 24. A tone source 26 is coupled to the primary winding of a transformer the secondary winding of which is connected in push-pull relation between the control grids of 22 and 24. The potentiometer resistor PR across a direct current source not shown supplies operating potentials for the tube 18 and the tubes 22 and 24. The tone keyer arrangement is such that when tube 18 is conductive the potential drop in the resistor 20 biases the tubes 22 and 24 to cut off thereby blocking energy of tone frequency supplied by source 26 from being applied to the output lines 30. When tube 18 is cut off the potential at the anode end of resistor 20 rises that is becomes more positive to turn on the tubes 22 and 24 to permit energy of tone frequency from source 26 to be fed to the outgoing lines 30. This might be the mark condition in the system. A similar tone keyer is shown and claimed in my U. S. Patent #2,237,631 dated April 8, 1941.

The condenser C is relatively large and with resistor R1, which may be in the discriminator detector output, operates as described in my U. S. application Serial #630,428 filed November 28, 1945 to supply to the control grid 17 potentials the polarity of which reverses with the keying even though the incoming wave is miscentered with respect to the discriminator characteristic. Unilateral devices in the form of diodes 32 and 34 are connected as shown in opposed polarity between the input terminal of resistor 15 and

ground. Sources 33 and 35 are in these connections. As the signal potential swings back and forth a direct current component is developed in the resistor R1 but cannot be applied through condenser C to the grid 17. Superimposed on this direct current voltage is a complex alternating current voltage representing the facsimile or telegraphy signal. As long as the incoming signal is centered the variations may be symmetrically related to a base value if desired and only the alternating components are transmitted to the grid 17. However if the center frequency of the incoming wave drifts there is a slow change in the direct current component across R1 and this voltage may be transmitted to some extent but is severely attenuated by condenser C. The tube 18 as a consequence is no longer subject to a direct current bias and its operation is not affected materially by slow changes in the detector output. The function of resistor 15 is to limit the grid current drawn by the tube 18 to a small value when the potential swings positive. Resistor 15 may be of the order of two megohms in a typical circuit while condenser C may be of the order of one mfd. and resistor R1 may be of the order of 100,000 ohms.

The apparatus and operation of the bias clamping tubes 32 and 34 will now be described. In this description reference will be made to Figure 4 of the drawings wherein is shown a characteristic typical of this tube and tone keying circuit. As increasing negative voltage is applied to the control grid 17, the tone keyer including tubes 22 and 24 begins to produce tone output at about minus one-half volt and comes to full output at about minus one and one-half volts. The tone output characteristic of these two tubes is shown by curve A in Figure 4. The voltage applied to the control grid 17 of the tone keyer tube 18 is shown by curve B. The output of the tone keyer remains constant for all values of signal potential applied to the grid 17 which exceed one and one-half volts negative and the output of the tone keyer is zero for all values of voltage applied to the control grid 17 from about one-half volt negative on up into the positive range of voltages. In a typical embodiment the voltage variation across resistor R1 in going from mark to space might be on the order of twenty volts. In that case I would like the bias fixing tubes 32 and 34 to function in such a manner that the control voltage applied to the grid 17 of tube 18 in the tone keyer swings from minus 11 volts on mark to plus 9 volts on space. This causes the tone keyer output to change from full on to full off at a point midway between mark and space voltages, which is desirable, to avoid telegraph bias when the signal shape is not the idealized square wave shown in Figure 4. In other words since the tone keyer 18 turns on and off for biasing potentials as fixed by the bias clamping tubes 32 and 34 well within the peaks of the signal or control potential excursions mutilations therein or rounding off of the corners thereof are unable to affect control of the tone keyer and as a consequence introduce telegraph bias in the tone output.

To accomplish this desired positioning of the voltage wave on the control grid 17 the bias of clamp diode 32 is in the example given about 9 volts positive while the bias of clamp tube 34 is about 11 volts negative. The cathode of the tube 32 is for example made positive with respect to ground about 9 volts by source 33 while the anode of tube 34 is made negative with respect to ground about 11 volts by source 35. Thus in the

example given the potentials on the right hand end of condenser C must swing more than 9 volts on the positive excursions to make tube 32 conductive and more than 11 volts on the negative excursions to make tube 34 conductive.

Now if the signal voltage wave is not centered as desired one or the other of the two clamp diodes 32 and 34 will draw current which will place a charge on condenser C in the proper polarity and of sufficient magnitude to cause the wave at the tone keyer control grid 17 to be properly centered. (-11 v. on mark; +9 v. on space). For instance assume that the frequency of the input at 19 has drifted so that the signal wave at resistor R1 swings from minus 5 volts for mark to plus 15 volts for space. When the signal is on space with plus 15 volts, the unidirectional conducting device 32 draws current through resistor R1 to place a negative voltage charge across condenser C. This negative voltage charge will amount to about 6 volts (15-9). The voltage impressed on the input of resistor 15 feeding the control grid 17 will be the algebraic sum of the voltage across resistor R1 and the charge voltage across condenser C. In this example then on space a voltage equal to plus 15 plus minus 6 or plus 9 volts will be fed to the input of resistor 15. On the negative excursions of the signal to record mark the voltage applied to the input end of resistor 15 is equal to minus 5 volts plus minus 6 volts or minus 11 volts on mark. The same kind of action takes place if the frequency drifts in the other direction so that there is an excess of negative bias. In that case diode 34 draws current which places a positive charge on the condenser C of a magnitude which will result in proper tone keyer operation.

Now returning to the example given above, wherein the mis-centered wave results in swings of +15 on space to -5 on mark and a negative bias of -6 volts is built up across condenser C and a space voltage of +9 is applied to the resistor 15, if due to noise or other effects this 9 volts is exceeded materially diode 32 will conduct and square off or limit the wave. In somewhat like manner if on mark a voltage in excess of -11 volts is applied to resistor 15 diode 34 will conduct to limit and square off the mark voltages.

In the embodiment of Figure 1 when the grid 17 swings positive grid current will flow but this grid current is limited to a small value by resistor 15. However the small grid current does introduce dissymmetry in the circuit because when the grid 17 swings negative the tube is cut off and no grid current flows. Obviously it is preferable to have equal leakage or biasing circuit current flow on both excursions of the signal being recorded so that the discharging or the leakage paths have equal current flow thereon on positive and negative swings and these discharge paths have no effect on the bias centering. In Figure 2 I provide similar leakage paths for both swings of marking potentials. The first path includes resistor 15 as in Figure 1. An additional path including tube 18' with resistor 15' is provided. When the potential on control grid 17 swings negative the cathode of tube 18' also swings negative to make this tube conductive at nearly the same instant tube 18 becomes non-conductive. When the control grid of tube 17 is swung positive grid current flows in the resistor 15 of an amount substantially equal to that flowing in the resistor 15' when tube 18 is conductive. On the positive swings tube 18' is cut off so that no current flows in resistor 15'.

Now the discharge paths are equal on both swings of the signal voltage.

In the embodiment of Figures 1 and 2 when signalling has stopped the charge on condenser C will leak off slowly so that after a few seconds the tone keyer control grid 17 voltage will be near zero potential and small negative excursions due to atmospheric noise will cause the tone keyer to be non-conductive to increase its anode potential and cause the tubes 22 and 24 to transmit bursts of tone to the output lines. These bursts of tone due to noise during idle periods will in some instances prove disturbing to the radio operator. In Figure 3 I show means which serve to block off or squelch the operation of the tone keyer as long as noise peaks are below a set threshold value. This set value is of course, smaller than the normal signal value. This means includes an electron control device 36 having its cathode connected to the input end of resistor 15 and its anode circuit coupled to the control grid 39 of an additional tube 40 supplied with potential from the common source and from a source 49 holding the cathode of tube 40 negative with respect to ground. The grid 39 is connected to the cathode by a biasing resistor 50 which is shunted by condenser 37. The tube 36 and its circuit serve to block off the operation of the tone keyer as long as noise peaks are below a set threshold value which is smaller than the normal signal value. When signalling is resumed the squelch circuit is immediately blocked off so that it does not interfere with normal signalling.

Assume that the signalling at the output of potentiometer R1 swings from plus 10 volts for space to minus 10 volts for mark. Also assume that the bias source 49 holds the cathode of tube 40 seven (7) volts negative with respect to ground. Then when the signalling potential at resistor 15 swings negative 10 volts on mark, condenser 37 charges to about minus 3 volts thereby biasing tube 40 to cut-off and hence tube 40 has no effect on the operation of the tone keyer during normal signalling. In this respect note that when the potential at resistor 15 swings in the positive direction the tube 36 is non-conductive. Resistor 50 is of such a value as to discharge condenser 37 very slowly, say on the order of 3 seconds. If signalling stops there will no longer be negative swings on the cathode of diode 36 and condenser 37 gradually discharges allowing tube 40 to draw current through resistor 20 to make more negative the potential at the anode end thereof to keep tubes 22 and 24 blocked off as they would be in the space condition.

In the embodiments described hereinbefore and illustrated in Figures 1, 2 and 3 I have shown my improved bias centering, and bias clamping, and tone keyer grid current compensating, and noise squelching circuit as being used with single receivers and conventional detector systems. It is equally advantageous to use my improved circuit arrangements in diversity systems of all types and in particular in diversity systems of the locking circuit controlled gating tube type. For example, my improved bias centering circuits and so forth may be connected to the output of the gating tubes of a system as disclosed in Schock et al. U.S. application Serial #632,978, filed December 5, 1945. Then the signal centering, and bias clamping, and compensating and squelching circuits may supply a tone keyer as in Figures 1, 2, 3, 5 and 6 or locking circuit stages in turn supplying a tone keyer or teletypewriter as in said Schock et al. application. In the embodiments of

Figures 5 and 6, reference numerals for the gating tubes and their control circuits corresponding to those used in the said application are used insofar as possible. The several signal versions are applied through condensers 16 and 16' to the control grids 19 and 19' of gating tubes 80 and 80'. Whichever gating tube is open amplifies the detected signal and the same appears across a common load impedance. In Figure 5 this load impedance also serves the function of the resistor R1 in Fig. 1. The resistor R1, condenser C and diodes 32 and 34 serve to center and limit and clamp and so forth the keyed potentials applied to the control grid 54 of the coupling tube 60 substantially in the same manner as these functions are accomplished by R1, C and so forth in Figure 1 of the drawings. The tube 60 operates as a cathode follower stage with resistance 57 as its output impedance. The coupling tube 60 supplies the keyed signals through a low pass filtering network 10 to the control grid 17 of the tone keyer tube 18.

Clamp tube 32 keeps grid 54 from going positive. Hence grid 54 goes from 0 to some negative value of voltage. This negative limit is established by clamp tube 34 and bias voltage 55. For 0 volts on grid 54, the plate current thru resistor 57 generates a voltage approximately equal to voltage of bias 55 so the resultant voltage applied to input of resistor 58 is approximately zero, for which condition tube 18 draws current, and no tone is transmitted by the tone keyer.

When grid 54 goes negative, the plate current thru resistor 57 decreases making the I. R. drop in resistor 57 less than the bias 55 so that the resultant is a negative voltage applied to resistor 58, which in turn causes cut-off of plate current in tube 18, which causes tone output to be transmitted.

When there is no keying present, the charge on capacitor C leaks off thru high resistance 53 so that the voltage on grid 54 is the negative voltage of bias 55. This results in a relatively small value of plate current thru resistor 57 so that the resultant is a negative voltage applied to resistor 58, which cuts off plate current in tube 18 and causes tone to be transmitted by the tone keyer.

In the preferred embodiment of Figure 6 the anodes of the gating tubes are coupled to a common load impedance 275 as in said Schock et al. application. One of the gating tubes is turned on by the control potential applied to its first control grid 264 or 264' so that the detected signals appear across resistor 275 and are fed by condenser 86 to the potentiometer resistor 88. A coupling tube 60' in this embodiment precedes the low pass filter 10. The coupling tube 60' is of the cathode follower type so that amplified or relayed signal potentials are fed to low pass filter 10 and appear across resistor R1 which is of the load circuit of tube 60' and also with capacitor C and clamp tubes 32 and 34 serves the purpose described hereinbefore. The signal variations at R1 follow the signal variations at the grid of tube 60' and the coupling tube 60' in this embodiment with tubes 32 and 34 and resistors 53, 57 and 58 function as described above in connection with Figure 5 to generate in resistor 57 a voltage about equal to the voltage 55 when the potential on the grid 54 is zero so that then the voltage at the input end of resistor 58 is about zero and tube 18 draws current. When the grid 54 swings negative (mark) the drop through 57 decreases and the bias 55 predominates to cut-off plate current in tube 18 and send out tone energy. When there

is no signal applied to the tube 60' the charge on capacitor C leaks off through high resistance 53 and the bias on grid 54 rises to a negative value set by bias source 55. The plate current through 57 is reduced and a negative voltage is applied to the resistor 58 to cut-off plate current in tube 18 to send out tone current.

What is claimed is:

1. In a signalling system in combination, an impediment across which a signal potential appears which potential varies in magnitude between maximum and minimum values separated by a substantially fixed amount, said potential being of an average value which may vary slowly to thereby change said maximum and minimum values, an electron discharge device having a control grid coupled to said impediment to be potential modulated in accordance with the signal potential through a selected substantially fixed range of substantially fixed average value, means in the said coupling for preventing changes in the average value of said signal potential from materially changing the average value of said potential modulation of said grid and means in said coupling for preventing variations in the magnitude of said potential modulation from exceeding selected maximum and minimum values.

2. A system as recited in claim 1 wherein said first means includes said impediment and a relatively large capacitor between said impediment and the control grid.

3. A system as recited in claim 1 wherein said device includes a cathode and wherein said last named means includes diodes shunting the grid to cathode impedance of said device in opposed polarity.

4. In a signalling system in combination, an impedance across which a signal potential appears which potential varies in magnitude between maximum and minimum values separated by a substantially fixed amount, said potential being of an average value which may vary slowly to thereby change said maximum and minimum values, an electron discharge device having a control grid coupled to said impedance to be potential modulated in accordance with the signal potential through a selected range above and below a selected base value, means in said coupling for adjusting said base value, to thereby also adjust the limits of said potential modulation range, means in said coupling for preventing changes in the average value of said signal potential from changing the base value of said potential modulation of said grid and means in said coupling for preventing variations in the magnitude of said potential modulation from exceeding selected maximum and minimum values.

5. A system as recited in claim 4 wherein said device includes a cathode and wherein said second and third means includes diodes in opposed polarity in shunt to the grid to cathode impedance of said device and means for applying an adjustable bias to at least one of said diodes.

6. In a telegraphy system in combination, an impedance wherein a potential is produced which varies in magnitude in accordance with telegraphy signals, an electron discharge device having a cathode and having a control grid to be potential modulated through a selected range, a coupling between one end of said impedance and the cathode of said device, a relatively large capacitor coupling the other end of said impedance to said control grid, a discharging circuit for said capacitor including resistance of a value such that the product of the capacitance of the ca-

pacitor and said resistance is large as compared to the rate of variation of said first named potential, said resistance including a diode coupled in shunt to said control grid and cathode and means for limiting variations in said potential modulation between two substantially fixed values including said first diode and a second diode coupled in opposed polarity between the control grid and cathode of said device.

7. In a receiving system for frequency shift telegraphy and facsimile in combination, a resistor wherein signals having an alternating current component and a direct current component appear, said alternating current component being of a magnitude which changes in accordance with signals about a base value, and means for eliminating said direct current component and establishing said base value as desired including output terminals, a relatively large capacitor coupling the high potential end of said resistor to one output terminal, a connection between the other end of said resistor and the other output terminal, a first diode having its anode coupled to said one output terminal and its cathode connected to said other output terminal, a second diode having its cathode coupled to said one output terminal and its anode coupled to said other output terminal and means for applying an adjustable voltage to at least one diode for biasing the same as desired.

8. In a signalling system, a source of potential which changes between two values in accordance with signals, a tube having a biased control grid and having a cathode and having output electrodes coupled to signal reproducing apparatus, means for impressing said signal potential between the control grid and cathode of said tube to modify the current flow in the output electrodes of the tube, and means for compensating the effect of variations in the grid current of said tube on the bias thereof for different values of said impressed potential including a second tube having an anode and a control grid and having a cathode excited by said potential, and a coupling between the control grid of the last tube and the cathode of the first tube.

9. A system as recited in claim 1 including means for compensating for the effect of changes in the grid current of said device with variations in the magnitude of the potential modulation.

10. A system as recited in claim 1 including means for compensating for the effect of changes in the grid current of said device with variations in the magnitude of the potential modulation including, a second electron discharge device having its cathode coupled to the control grid of said first device and its control grid coupled to the cathode of said first device.

11. A system as recited in claim 8 including means for rendering said first tube ineffective to actuate said signal reproducing apparatus in the absence of impressed signal potentials for a selected time period.

12. In a system for recording signal potentials which vary between two values representing different signalling conditions, an electron discharge device having output electrodes and having a control grid coupled to said impedance to be potential modulated in accordance with the signal potentials through a selected substantially fixed range of substantially fixed average value, signal reproducing means coupled to said output electrodes, and means for rendering said device inoperative to control said signal reproducing means when said potential modulation is inter-

rupted for a selected time period including a diode having its cathode coupled to the control grid of said device and its anode coupled by a capacitor and a negative source of potential to the cathode of said device, a resistor in shunt to said capacitor and a second electron discharge device having its control grid and cathode in shunt to said last named resistor and its output electrodes in parallel with the output electrodes of said first device.

13. In a system for recording signal potentials which vary between two values representing different signalling conditions, said potentials being of an average value which may vary slowly to thereby change said two different values, an electron discharge device having output electrodes and having a control grid coupled to an impedance to be potential modulated in accordance with the signal potentials through a selected substantially fixed range of substantially fixed average value, means in said coupling for preventing changes in the average value of said signal potential from materially changing the average value of said potential modulation of said grid, signal reproducing means coupled to said output electrodes, and means for rendering said device inoperative to control said signal reproducing means in the absence of potential modulation including a diode having its cathode coupled to the control grid of said device and its anode coupled by a capacitor and a negative source of potential to the cathode of said device, a resistor in shunt to said capacitor and a second electron discharge device having its control grid and cathode in shunt to said last named resistor and its output electrodes in parallel with the output electrodes of said first device.

14. In a system for recording signal potentials which vary between two values representing different signalling conditions, said potentials being of an average value which may vary slowly to thereby change said two different values, an electron discharge device having a control grid coupled to said impedance to be potential modulated in accordance with the signal potentials through a selected substantially fixed range of substantially fixed average value, means in said coupling for preventing changes in the average value of said signal potential from materially changing the average value of said potential modulation of said grid, means in said coupling for preventing variations in the magnitude of said potential modulation from exceeding selected maximum and minimum values, means for compensating for changes in the grid current in said device caused by changes in the magnitude of said potential modulation, and means for rendering said device inoperative to control said signal reproducing means in the absence of potential modulation.

15. In a signalling system, a source of signals which changes between about zero potential which represents one signalling condition and a negative potential which represents a second signalling condition, a control tube having a control grid and cathode and having output electrodes arranged to operate signal reproducing apparatus, means for impressing said potential on the control grid of said tube to modify the current flow between the output electrodes of the tube, said means including a diode having its cathode coupled to the grid of said tube and its anode connected to the cathode of said tube, and means for reestablishing a negative potential on said grid of the order of said first.

mentioned negative potential when no signals are applied to said grid and the negative potential built up on said grid leaks off because of said diode.

16. A system as recited in claim 15 wherein said last named means includes a source of potential and a resistor connected between the anode of said diode and the cathode of said tube, and a second resistor in shunt to said diode.

17. In a signalling system for frequency shift telegraphy and facsimile in combination, a resistor wherein signals having an alternating current component and a direct component appear said alternating current component being of a magnitude which changes in accordance with signals about a base value which may vary in an undesired manner, and means for eliminating the effect of variations of said base value and for establishing said base value as desired including an electron discharge coupling tube having a control grid coupled to said resistor, said tube having output electrodes including a cathode, a control tube having output electrodes coupled to a utilization circuit and having a control grid and cathode, a filter coupling the cathode of said first tube to the control grid of said second tube, said filter including an impedance in the cathode return circuit of said first tube, and a relatively large series capacitor and shunting diodes of opposed polarity in said first or third coupling.

18. In a signal recording system in combination, a resistor wherein signals having an alternating current component and a direct current component about which said alternating current component alternates in accordance with different signalling conditions appear, means for eliminating said direct current component and establishing a new base value around which an alternating current component representing the signals varies as desired including an electron discharge device having output electrodes including a load impedance coupled to utilization means and to a source of direct current potential, a two conductor circuit including in one lead a relatively large capacitor and resistor in series connected from spaced points on said first resistor to the control grid and cathode of said tube, two diodes connected in opposed polarity through potential sources of opposed polarity in shunt to said two conductors, a second electron discharge device having output electrodes including an anode coupled to said source of direct current through said load impedance and including a cathode connected by a source of potential to the cathode of said first device, a diode and a capacity in series connecting the high potential side of said two conductor circuit to the cathode of said second electron discharge device and a resistance in shunt to the control grid and cathode impedance of said second device.
